MERRY-GO-ROUND

Filed Jan. 15, 1930

2 Sheets-Sheet 2

UNITED STATES PATENT OFFICE

R T JONES, OF PERRY, IOWA

MERRY-GO-ROUND

Application filed January 15, 1930. Serial No. 420,894.

The object of this invention is to provide an improved construction for a play ground circular swing or merry-go-round for use by children.

5 A further object of the invention is to provide an improved merry-go-round of the low enclosed type which provides sufficient safeguards for the protection of children using it.

10 Still another object of the invention is to provide a merry-go-round which may be propelled by the wind or by foot actuation of some of its occupants, or by a combination of such forces.

15 Another and further object of the invention is to provide a merry-go-round having hinged vanes arranged to be engaged by the wind at certain portions of the rotation of the machine and to drop down to inoperative position during other portions of such rotation.

20 Still another object of the invention is to provide improved means for mounting the structure for rotation and for insuring ample support and balance at all times during its 25 rotary travel, regardless of the distribution of weight thereon.

Another object of the invention is to provide an improved adjustable seat to be occupied by an operator.

30 With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a plan view of my improved 40 merry-go-round.

Figure 2 is a side elevation of the same.

Figure 3 is a bottom plan view of the merry-go-round removed from its support.

45 Figure 4 is a vertical section radially of the device on the line 4-4 of Figure 1.

Figure 5 is a detail section illustrating the adjustable seat and driving wheel construction on the line 5-5 of Figure 4.

50 Figure 6 is a detail horizontal section

through the adjustable seat structure on the line 6-6 of Figure 5.

Figure 7 is a perspective view illustrating one of the brakes employed for checking the speed of the merry-go-round.

55 A suitable foundation and support is provided for the merry-go-round which preferably consists of a concrete slab 10 resting on or partially within the ground and this slab may be and preferably is provided with metal track facing 12 of annular form.

60 The concrete slab 10 is formed at its center with an upwardly opening socket 14 equipped with a step bearing 16 preferably of anti-friction type.

65 The merry-go-round proper has a central post 18 which has its lower end arranged to be mounted in the socket 14 in contact with the step bearing 16.

70 The post 18 is provided near its lower end with an annular plate 20 and near its upper end with an annular plate 22. A series of supporting arms 24 are fixed to and radiate from the lowermost plate 20 and a series of supporting arms 26 are fixed to and radiate 75 from the uppermost plate 22.

75 The outer ends of the lowermost supporting arms 24 are rigidly connected by platform members 28 and also seat members 30 which are elevated relative to the platform members.

80 The uppermost supporting arms 26 are of less length than the lowermost supporting arms and are turned downwardly at their outer ends to form supports for backrest members 32 which cooperate with seat members 30.

85 The platform members 28, seat members 30 and backrest members 32 provide accommodations for children who wish to ride on the merry-go-round and it will be noted that these members extend substantially around the device so that considerable capacity is provided for occupants.

90 The outer ends of the lowermost supporting arms 24 also are rigidly connected by angle bars 34 which serve as foot rails for the occupants. The foot rails 34 lend rigidity to the structure and also are desirable for engagement by the feet of the occupants to 95

resist centrifugal force when the machine is in rapid motion, it being noted that normally the occupants are seated so as to face outwardly of the machine.

5 The machine is provided with a cover composed of segmental plates 36 resting on and secured to the uppermost supporting arms 26, so that the machine is substantially enclosed. In this connection it will be noted 10 that the platform members 28 and foot rails 34 are arranged to travel quite close to the surface of the ground so that none of the occupants are able to get under or within the machine while it is in motion and thus 15 run the risk of injury.

I also provide a series of hand rails 38 which are fixed at their lower ends to the undersurfaces of the lowermost supporting arms 24 and which extend upwardly and inwardly and are attached at their other ends to the uppermost supporting arms 26. The hand rails are for the convenience of occupants in mounting to or dismounting from the machine, and also for applying force to 25 set it in motion.

I have provided a pair of driving wheels 40 which are arranged on opposite sides of the center post 18 and are designed to travel on the track 12. I also provide a pair of 30 idler wheels 42 which are oppositely arranged and are designed to engage the track 12 at times although they are normally spaced slightly above the surface of the track as indicated in Figure 2. The wheels 40 and 35 42 may be supported by some cross bars 44 which connect the lowermost supporting arms 24.

The pivots of the idler wheels 42 are supported by certain of the cross bars 44 and 40 by other bars 46 parallel thereto in such manner that their peripheries are normally spaced a slight distance above the track 12. In case of uneven distribution of the weight 45 on the merry-go-round, or in the event the track surfaces are not entirely level and uniform, the wheels 42 will engage the track at times and will thus serve to balance and properly support the merry-go-round for rotation.

50 The driving wheels 40 are arranged between certain of the cross bars 44 and other cross bars 46 and are rigidly attached to axles 48 which are extended beyond the cross bars 46 toward the periphery of the machine. I have provided a cushioned mounting for the 55 axles 48 of the driving wheels in order that there may be some relative movement of the wheels and frame of the machine to compensate for uneven track surfaces and for unequal distribution of weight on the machine.

As shown in Figures 4 and 5, each of the axles 48 is journaled in a bearing 40 which is of H shape in plan view and is slidably mounted in a boxing 52 suspended from the 60 cross bars 46 and otherwise suitably support-

ed as by bars 54 connecting certain of the lowermost supporting arms 24. A relatively stiff coil spring 56 is mounted in the boxing 52 between the bearing 50 and the cross bar 46 and serves as a cushioned means for transmitting weight from the frame of the machine to the driving wheel 40.

Opposite each of the driving wheels 40 and at the outermost periphery of the machine, in line with the peripheral platform and seat, 70 I have provided an open cock pit and these cock pits are designated as A and B.

Each of the cock pits A and B is formed by cutting away portions of the platform members and seat members for mounting a box 80 like wall 58 in such opening, said wall being open at its bottom and at its top.

The driving shaft or axle 48 of each of the driving wheels 40 is extended across one 85 of the cock pits and is provided at its outer end with a bearing 60 carried by the outer wall of the cock pit. Within the cock pit each driving shaft 48 is provided with opposed cranks 62 and 64 which are adapted for foot actuation to turn the driving wheels.

90 A seat is provided in each of the cock pits A and B and I have here shown the seat adjustably mounted on and carried by the rear wall of the cock pit, which wall is extended upwardly above the remaining walls and is designated by the numeral 66, said member forming a backrest for the seat.

The backrest 66 is formed with spaced slots 68 and 70 arranged vertically and is also provided on its rear face with a pair of vertically arranged angle bars 72 and 74, each of which is formed with a plurality of notches 76.

100 The seat member is designated by the numeral 78 and is provided with a rearwardly and downwardly inclined brace 80 which carries a shoe 82 which loosely engages the forward face of the backrest 66.

105 The seat member 78 is formed at its rear margin with a pair of rearwardly directed fingers 84, which fingers extend loosely through the slots 68 and 70 and terminate in laterally directed lugs 86 which are adapted to engage the notches 76 of the respective angle bars 72 and 74.

110 The seat member 78 may be adjusted vertically on the backrest 66 by tipping it rearwardly a sufficient distance to cause the lugs 86 to disengage from the notches 76, after which the seat member may be moved up or 115 down the desired distance. When placed in the desired position the lugs 86 are again caused to enter certain of the notches 76 and the seat assumes its normal horizontal position with the shoe 82 resting against the back 120 member 66 and, together with said lugs, forming a support for the seat member.

125 The occupants of the cock pits A and B may adjust the seat members 78 to the desired position and may then seat themselves 130

thereon and operate the machine by pedaling with the cranks 62 and 64 to rotate the driving wheels 40 which are in forcible frictional contact with the track 12.

5 I have also provided means whereby the force of the wind may be utilized in whole or in part for causing rotary movement of the merry-go-round.

10 A plurality of vanes 88 are mounted on the cover members 36 of the machine and are pivotally attached at their leading edges to the uppermost supporting arms 26 by means of hinges 90. The trailing edges of the vanes 88 normally are held in slightly elevated position by means of stop lugs 92 carried by the cover of the machine so that air currents traveling in the proper direction may engage beneath the vanes and cause them to swing upwardly on their hinges so that the 15 air pressure will assist in causing the machine to rotate. When the machine has turned far enough that a given vane 88 is carried out of the course of the wind, it will be dropped back to inoperative position with its rear edge resting on a lug 92 until such time as said vane again comes into the course of the wind. In this manner a relatively slight wind will render considerable assistance in turning the merry-go-round. I have also provided a stop 20 94 fixed to the cover of the machine adjacent the leading edge of each vane 88 to limit the upward movement and thus provide the necessary resistance to the wind currents.

25 At times it may be desirable to employ braking means for retarding or stopping the travel of the machine and for this purpose I have provided the mechanism shown particularly in Figure 7.

30 A brake arm 96 is pivotally attached at its forward end by means of a bracket 98 to one of the lowermost supporting arms 24 and carries at its rear end a brake shoe 100 adapted to engage the track 12.

35 A rock shaft 102 is journaled in bearings 104 and has at one end a crank arm 106 pivotally attached by means of a link 108 to the rear end of the brake arm 96.

40 The opposite end of the rock shaft 102 is provided with a hand crank 110 located adjacent one of the cock pits and adapted for manipulation to force the brake shoe 100 downwardly into frictional engagement with the track surface. If desired, a spring 112 may be employed for raising the brake shoe 45 when manual pressure is released. If desired, one of the brake devices may be located adjacent each of the cock pits A and B.

50 My improved merry-go-round is of substantial and durable construction and is compact and of considerable passenger capacity for its size.

55 The method of mounting the merry-go-round for turning movement on the step bearing for the center post 18 and on the driving wheels 40 makes it very easy to propel

and it has been found that this merry-go-round can easily be operated by one or two small children and also that the wind vanes greatly assist in the propulsion of the machine.

70

I claim as my invention:—

1. In a merry-go-round, a support including a step bearing and a track concentric therewith, a center post having its lower end engaging in said step bearing, a frame including arms radiating from said post, a substantially annular passenger support carried by said arms, driving wheels carried by said frame and adapted to travel on said track, means carried by the frame for causing rotation of said wheels, and wind vanes arranged in substantially horizontal positions on top of the frame, said vanes being hinged at their leading edges whereby they may be raised by wind currents to provide propelling means for the device.

75 2. In a merry-go-round, a frame, a stationary track, a driving wheel on the frame arranged to engage and travel on the track, a cock pit at the outer part of the frame opposite said driving wheel, a seat in said cock pit, a driving shaft fixed to said driving wheel and extending within the cock pit, said driving shaft being formed with opposed cranks for foot actuation by an occupant of 80 the seat in said cockpit.

85 3. In a merry-go-round, a frame arranged for rotary movement, passenger supports on said frame, a substantially imperforate cover on the top of the frame, and a series of wind vanes on said cover and hinged at their leading edges, together with means for slightly supporting the free edges of said vanes and means to limit upward swinging on their 90 hinges, whereby said vanes will be raised by wind currents engaging them from the rear and will serve as propelling means for the merry-go-round, and will drop by gravity to inoperative position when they have moved out of the course of the wind currents.

100 4. A merry-go-round, comprising a central support, a track concentric therewith, a frame having arms radiating from said support and rotatable thereabout, a substantially annular passenger support carried by said arms, a 105 driving wheel carried by said frame and adapted to travel on said track, means carried by the frame for causing rotation of said wheel, and wind vanes arranged on said frame, said vanes being hinged to the frame 110 at their leading margins whereby they may be lifted by wind currents to provide propelling means for the device.

115 Des Moines, Iowa, December 27, 1929.

R T JONES. 125
